UNITED STATES PATENT OFFICE

FRANCIS E. ASHTON, OF CHESTER, PENNSYLVANIA, ASSIGNOR TO ABERFOYLE MANUFACTURING COMPANY, OF CHESTER, PENNSYLVANIA, A CORPORATION OF PENNSYLVANIA

LOOM

Application filed January 31, 1928. Serial No. 250,790.

This invention relates to a loom for weaving double fabrics such as plush and face and back fabrics.

The loom of this invention is akin to an application for improvement in loom, filed by this applicant on December 24th, 1927, Serial No. 242,342, and much of the mechanism illustrated and described in that application is shown and will be described in connection with the present invention.

The object of this invention is to provide an improved loom for weaving double fabrics such as plush and face and back material.

Another object of the invention is to provide a loom which is highly efficient, has fewer and simpler parts, and by the use of which the cost of producing plush fabrics and front and back fabrics is materially reduced.

Another object is to provide a loom for weaving plush and face and back fabrics in which shuttles, shuttle boxes and picker mechanism is entirely eliminated.

Another object of this invention is to provide a loom in which a greater variety of colors of weft threads may be used.

Another object is to provide an improved loom for weaving plush fabric and face and back fabric and the like in which there is less likelihood of defects such as caused by weft ends.

This improved loom for weaving plush fabrics and face and back fabrics and the like also has the additional advantages set forth in the pending application above referred to and which may be summarized as follows:—

The cost of winding bobbins is eliminated as no bobbins are used; the initial cost and the cost of maintaining shuttles and shuttle boxes is also saved as none of these elements are used; on account of the weft threads being fed directly from cones, the loom is capable of continuous operation as it is not necessary to stop the same to replace bobbins as in the conventional loom; the weft threads being supplied from an exterior and stationary source may be replenished at any time without stopping the loom.

The loom is practically noiseless in operation and a great advantage is that the danger from flying shuttles and broken parts of shuttles and shuttle boxes will be entirely eliminated.

According to the invention the improved loom for weaving plush fabrics, front and back fabrics, and the like, has warp beams and heddles for producing upon each operation a pair of warp sheds; means for positioning weft threads so that any selected color may be engaged by carriers which project each of the selected threads to the center of one of the sheds where each is received by a needle, disengaged from the carrier, and carried to the other side of the shed at which point both weft threads are cut by suitable cutting means which also acts as a stop mechanism when either of the weft threads is wanting; and means for actuating the carriers and needles.

The drawings illustrate an embodiment of the invention and the views therein are as follows:—

Figure 1 is a front view of an improved loom,

Figure 2 is an elevational view from the left end of the loom with the top, pattern chain, harness and other parts omitted,

Figure 3 is a partial section on the line 3—3 of Figure 2,

Figure 4 is a plan view of the right side of the loom with a portion of the front broken out and shows an arrangement of the weft cone and feeds therefrom,

Figure 5 is an enlarged fragmentary section, taken on the line 5—5 of Figure 4, looking in the direction of the arrows,

Figure 6 is a fragmentary vertical section taken on the line 6—6 of Figure 1, and shows the means for severing the weft threads, releasing them from the needles, and means for stopping the loom when the weft thread is omitted from either shed,

Figure 7 is a horizontal section taken on the line 7—7 of Figure 1, and shows the operative mounting for the carrier which is identical with the mounting for the needle,

Figure 8 is a partial plan of the loom with the center removed and shows the weft

Figure 11 a top plan view of the carrier,

Figure 12 a side view of the same,

Figure 13 is a side view showing the carriers and needles in the position in which they engage at the approximate center of the sheds and at the time that the weft threads have been pushed down under the needle so that upon the separation of the carriers and needles the threads will be retained by the latter.

Figure 14 is a vertical section on the line 14—14 of Figure 1 looking in the direction of the arrows,

Figure 15 is a perspective view of one of the bifurcated swivel clamps which engage the levers for actuating the carriers and needles,

Figure 16 is a like view of the swivel mounting,

Figure 17 is an enlarged section through the weft threads of a face and back fabric and shows the manner in which the warp sheds are provided for weaving the weft threads,

Figure 18 is a like view of plush fabric and in addition to the separate warps for weaving the face and back of the fabrics shows an additional warp shed which provides the fell or nap, and

Figure 19 is a fragmentary sectional view taken on line 19—19 of Figure 8, looking in the direction of the arrows.

Like parts in each of the figures of the drawings are characterized by like reference numerals.

40 The loom comprises a frame 30, arches 31, dobby 32, pattern cylinder 32', breast beam 33, hand rail 34, lay 35, reeds 35', swords 36 for carrying the lay and hand rail, temples 37', pulleys 37 and shipper handle 38.

45 These parts are arranged in the usual customary manner and operate in the same way as the conventional loom.

The pulley is provided with a gear 39 which meshes with a large gear 41 on the main drive shaft 42. This drive shaft is mounted in suitable bearings 43 on each side of the loom frame and is extended therefrom at each end and said shaft ends are mounted in bearings 44 supported on pedestals 46 which are suitably anchored by means of the bolt 47.

Needles and carriers

Figures 9 and 10 show a needle 45 such as adapted for use on this improved loom, and Figures 11 and 12 show a carrier 50, while Figure 13 shows the manner in which the needles and carriers cooperate to lay the warp threads in the upper and lower warp sheds.

The needles and carriers comprise the subject-matter of a patent granted to the applicant on June 10, 1930, Patent No. 1,762,377.

The needle has a threaded shank 48 which is secured in the end of a rod 49 and the carrier also has a threaded shank 48 which is secured in the end of a rod 51. The mounting of the rods 49 and 51 is identical so that the detail mechanism for the carrier only has been shown. Two of the rods 51, as shown in Figure 13, are suitably mounted between upper and lower slide bars 52 which are provided at the rear end with a suitable spacing block 53 and at the front end with a spacing block 54 which has bushings 56 in which the rods 51 are adapted to slide. These bushings may be replaced from time to time as the same wear by unscrewing the set screw and drawing the same over the carrier. The blocks 53 and 54 are each provided with an eye bolt 57 at a point near the center of one side of said blocks and the eye bolt has a lock nut 58 thereon for permanently securing the eye of the bolt at the required distance from the block after it has been properly adjusted. A rod 59 extends between and passes through the eyes of the eye bolts 57 and its ends are threaded and provided with nuts 61 on each side of each eye, and these nuts embrace the eye and clamp the rod securely in place. The rear ends of the rods 51 are mounted in a cross-head 62 which slides between the bars 52 and one side of the cross-head extends outward from said bars and has a hole 63 through the same through which the rod 59 passes by a sliding fit so that the said cross-head may move along the same and be guided thereby. On its other side the cross-head 62 is provided with a plate 64 which engages the outer faces of the bars 52 and this plate tends to prevent lateral movement of the cross-head in the slide bars 52. A bolt 66 extends into the cross-head on the same side as the plate 64 and through said plate and this bolt is provided with a lock nut 67 for positioning the same and securing it against rotation. A link 68 is pivotally mounted at its upper end between said nut and the head of said bolt. This mechanism is clearly shown in Figure 7 when considered in connection with Figure 13 and the mounting of the needles is exactly the same as that described except that the parts are in reverse position.

These slide bars 52 are mounted on extensions on each end of the lay 35 and the needles and carriers extend toward the center of the loom while the upper needle and upper carrier have a common longitudinal center and the lower needle and lower carrier also have a common longitudinal center.

The carriers 50 are provided with bifur-

cated arms 69 as shown in Figure 11, and each arm is provided with a slot 70 as shown in Figure 12. The needles 45 each have a lower lip 71 which is provided with a central passage 72 extending a short distance inward from the end of the same and said needle has an overhanging shoulder 73. Extending from the center of this shoulder is a hook 74 and the retracted end of this hook lies within the recess 72 on the lower lip 71 and is provided with a small space around the same to permit the weft thread to pass thereunder when engaged by the carrier. Figure 13 shows the manner in which the weft threads are transferred from the carriers to the needles.

Needle and carrier operating mechanism

Near each end of the drive shaft 42 is a drum 76 which has a continuous cam ridge 77 surrounding the same and this cam is provided with dwells 78 for retaining the needles and carriers in their retracted positions while the warp sheds are being changed by the dobby and the weft of each shed is being beaten into the fell of the face and back of the fabric respectively. A standard 79 is mounted near the end of the pedestal 46 and is provided at its upper end with a bar 81 which extends toward the loom frame and is bent at right angles near the inner end thereof and its downwardly turned end is fastened to an upright 82 secured to the loom frame by bolts 83. A slide bar 84 is slidably mounted in a square hole in a bracket 86 secured to the upright 82 and in a square hole in the angle bracket 87 secured to the outer end of the bar 81 and standard 79. This slide bar carries a cam follower consisting of a plate 88 pivotally mounted thereon by a pin 89, and the plate is provided with a pair of idle rolls 91 which are spaced to admit the cam ridge 77 between the same so that upon the rotation of the cam drum 76, the rolls 91 and plate 88 will follow the said cam ridge and the slide bar 84 will be moved to and fro in the square holes of the brackets 86 and 87. The pivotal pin 89 will permit the easy operation of the follower. The slide bar 84 is provided with a depending leg 92 at the lower end of which is a horizontally disposed pin 93 which extends under the bar 81 and pivotally connects with one end of a link 94 whose other end is pivotally connected at 96 to a lever 97 and this lever is pivotally connected at its upper end to the link 68 which is in turn pivotally secured on the bolt 66 carried by the cross-head 62 which operates in the slide bars 52.

An angle bracket 98 is mounted at a position near the center of the bar 81 and this bracket has an extending flange to which a swivel bracket 99 is securely fixed. This swivel bracket (see Figure 16) has a depend-

ing leg 101 which has holes 102 therethrough for securing it to the angle bracket by bolts passing through said holes and said swivel bracket has a main body portion 103 having a hole 104 for receiving a pin 106 extending outward from the bifurcated swivel 107 (see Figure 15). The lever 97 fits between the bifurcations of this swivel and is pivotally mounted therein. The pivotal mounting of a pin 106 permits the lever to be readily moved backward and forward as the lay is moved by the swords to beat the weft threads into the fell of the fabric.

The cam drum 76 may be so arranged on the drive shaft 42 that the needles may operate a trifle behind the carriers or vice versa so that the needles engage the carriers at the moment they are changing, or immediately after they change, their direction of travel. This will prevent any excessive tension or strain on the weft threads during the transfer from the carriers to the needles.

One revolution of the cam drums provides two complete operations of the needles and carriers and consequently two weaves of weft thread.

Selective mechanism for weft threads

On the right hand side of the loom frame 95 as viewed from the front thereof (see Figures 1 and 4), a platform 108 is suitably mounted. This platform is provided with a plurality of uprights for supporting any required number of cones 109 which carry 100 the weft threads. These cones are arranged in rows and the cones of each row are staggered in relation to the cones of the adjacent rows and each row is provided with an arched thread guide 111 over which the thread from the cones is drawn. These thread guides may be of different heights to insure no interference between the threads of the several cones, and may be made from heavy wire or thin rods bent to shape.

The weft threads which are drawn from the cones pass through eyelets in the guide plate 112 which is positioned vertically between the arches 31 and after passing through these eyelets, the weft threads pass through eyelets in the guide plate 113 and through eyelets in the guide plate 114, both of which latter-named guide plates are horizontally disposed. After the weft threads have passed through the thread guide 114 they pass through a vertical guide plate 115 which is secured to the loom frame and these threads pass through said guide horizontally, the weft threads for the upper warp shed being disposed in the upper eyelets and the weft threads for the lower weft shed being disposed in the lower eyelets. After leaving the eyelets in the guide plate 115 each individual weft thread passes through an eyelet 117 in the individually

operated heddle 118. The weft threads then pass through a wire guide 119 which confines them and from thence they pass to the selvage edges on the right hand side of the cloth C. The heddles 118 are suitably supported by heddle straps 131 which are in turn connected to the jack wires which pass over the pulleys 122 and are each connected with their respective jack 123 which is operated by the dobby 32 through the pattern chain 124 on the pattern cylinder 32'. The heddles are connected at their lower ends with long helical springs 126 which are in turn connected to the base of the machine or the floor 127 so that when released by the jacks the weft threads will be lowered.

By reference to Figure 5 and assuming that there are but four cones on the platform 108 and that two are used for the lower warp shed and two for the upper warp shed, two of the heddles, i. e. one carrying the weft of each shed will be in their lowered positions as shown at 125 and 130 while two of the heddles 125' and 130' each carrying the thread of the color selected for each of the warp sheds will be drawn upward. If desired each of the heddles may be provided with two eyelets, one carrying a weft for the upper shed and the other carrying a weft for the lower shed. All these warp threads pass in close proximity to the right hand side of the sheds formed by the warp threads which have been designated as 128 and 128' for the lower shed and 129 and 129' for the upper shed and the selected weft threads 132 and 132' will lie directly in the paths of the carriers 50 and against the fingers of the carriers which act as stops or limits to the upward movement of the selected threads. The pile shed composed of the warp threads 135 and 135' will be described later in connection with the description of Figure 18.

It will of course be understood that the selection of the weft threads, two of which are shown in position to be engaged by the carriers and which threads have been characterized by the numerals 132 and 132' will be controlled entirely from the pattern chain 45 acting through the dobby which operates the required jacks to raise the heddles carrying the selected colors of weft thread. The other weft threads (which in this particular instance where eight weft threads are shown, consist of six threads) will be disposed below the path of travel of their respective carriers and consequently will remain idle until such time as one or another of the same is selected for passage through 55 its warp shed by the pattern chain.

The wire guide 119 has its looped end disposed at an angle in order to draw the weft threads close together and confine them within a small area so that they can be readily engaged by the carriers when select-

ed and elevated to a position to be engaged thereby.

It will of course be understood that the weft threads which are passed through the upper warp shed consisting of the warp threads 129 and 129' will, when lowered, 70 repose between the paths of travel of the upper and lower selectors, sufficient clearness being provided so that when idle they will not interfere with the operation of the 75 carriers.

The platform 108 may be of any desired size and a great number of different colors of weft threads may be employed for weaving into both the upper and lower warp 80 sheds, and these weft threads being selected as they are by the pattern chain can be woven to simultaneously provide different patterns in the upper and lower warp sheds. Consequently, when face and back material 85 is being woven, the face and back may be of entirely different patterns, such for instance as a solid color for the face and a plaid design for the back.

Stop mechanism

The drive shaft 42 is provided with a cam 133 which operates a bell crank 134 whose upper end is provided with a pair of fingers 140 and 140' which are disposed one above 95 the other and which normally extend into a recess 136 in the upper and lower latches 137 and 137'. This cam is so shaped as to provide two actuations of the bell crank for each revolution of the shaft 42. The latches 100 137 and 137' are each pivotally mounted at the inner end between the open sides of a slide 138 and at the inner end thereof by means of a pivoting screw 139. These screws are each securely fixed in its 105 respective latch which tilts when its screw is turned. These pivoting screws extend outward from the right hand side of the slide and a knife 141 is securely fixed on each of said screws by means of suitable 110 lock nuts. The slide is mounted on the breast beam 33 between the guides 145 and is provided with a recess 142 near its outer end into which the end of a rocker arm 143 extends. This rocker arm is fixedly secured 115 by its other end to a shaft 144 which extends across the loom and is journaled in brackets 146 on each side thereof. This shaft is provided on the end opposite to that on which the rocker arm is fixed with a lever 147 which extends through a slot in the breast beam (see Figure 8).

The recesses 136 in the latches 137 and 137' each provide a rear wall 148 which is simultaneously raised by the weft threads 125 of the upper and lower warp shed to the positions shown by the dotted lines in Figure 6 so that the fingers 140 and 140' on the upper arm of the bell crank travel in the recess 149 in the slide when the latches are 130

tilted to raise the rear walls 148 out of the path of said fingers as the upper end of the bell crank is moved to and fro by the cam 132. This device is for the purpose of stopping the machine in case either of the weft threads is not engaged by its selector 50 and carried by its warp shed. The absence of either warp thread permits the respective latch to remain stationary and its rear wall 148 is then engaged by the finger corresponding to the omitted weft thread.

The operation is as follows:

In Figure 8 the needles are shown in their retracted positions and the weft threads are engaged and held thereby. The wefts at this point are indicated by the numeral 151, one being directly above the other. As the reed 35' carried by the lay and hand rail moves forward to beat the weft threads into the fell of the cloth, the weft threads are pressed against the knives 141 which tilt downward as shown by the dotted lines in Figure 6, and the latches 137 and 137' are rocked, thereby raising the end walls 148 above the path of the fingers 140 and 140'. The cam 133 is so positioned on the drive shaft 42 that it will operate the bell crank to move the fingers on the upper arm thereof at the same instant that the weft threads 151 strike against the knives 141 and tilt the latches 137 and 137' upward to clear the path for the fingers on the upper end of the bell crank so that they will pass unobstructed through the recess 149. In case either of the weft threads is omitted, for any reason, there is nothing to strike against the knife to tilt the latch 137 or the latch 137'; whichever the case may be, so that upon the actuation of the bell crank 133 by the cam 132, the finger on the upper end of the bell crank which operates in the latch adapted to be raised by the weft thread which has been omitted, will strike against the rear wall 148 of said latch and will move the slide and latch outward, thereby rocking the rocker arm 143 and rotating shaft 144 which in turn rocks the lever 147 causing it to strike against the pivoted trip 152 and move the shipper handle out of its locking groove 153 whereupon said shipper which is formed of spring metal will spring outward and stop the loom.

The product of the loom

Figure 17 illustrates the manner of weaving a face and back fabric. It will be noted that the weft threads which I have designated 154 constituting the face of the cloth are much finer than the wefts 156 which form the back of the cloth. However any design and diameter of threads may be used as desired. The pattern chain is so arranged that the upper warp shed which I have indicated by A and the lower warp shed indicated by B are changed by the heddles so as to intermittently pass a warp thread 157

from the face of the cloth to the back of the cloth and vice versa. These transverse warp threads 157 connect the face and back of the cloth together so that when finished it presents the appearance of a single piece of fabric having different designs or patterns on its face and back.

Figure 18 illustrates a manner in which the plush fabric is produced.

For this description refer also to Figure 5 which shows the pile shed formed by the warp threads 135 and 135'. The lower shed is formed by the warp threads 128 and 128' and the upper shed by the warp threads 129 and 129'. The selected weft threads are shown at 131 and 131'. These threads having been woven into the upper and lower sheds by the carriers and needles are beaten into the fell of the lower and upper faces of the cloth respectively by the reed which is carried on the lay. It will be noted that the pile shed is constantly changed or the threads 135 and 135' alternated in order to form the transverse threads which are indicated by the numeral 158 and which form the pile or nap of the fabric. The warp threads for providing the pile shed and consequently the pile threads 158 are carried on a separate warp beam (not shown as this is present in the conventional loom), and this beam travels considerably faster than the main warp beam carrying the warp threads 128, 128', 129 and 129' as greater lengths of the pile warp are being constantly woven into the material.

These views are, of course, greatly enlarged and are to a certain extent diagrammatic in order that the weaving may be readily understood and the plush material is produced by cutting the pile threads at a point equidistant from the faces formed by the weft threads 131 and 131' in order to produce two separate lengths of plush fabric.

It will of course be understood that the loom may be utilized by arranging the pattern chain to produce any desired double faced fabric and, if desired, two separate and unconnected lengths of cloth may be simultaneously produced in a loom designed in accordance with this invention.

Operation of the loom

The cones containing the required colors for weaving the weft into the face and back sheds of the fabric are placed upon the uprights on the platform 108 and the proper threads are drawn through the eyelets in the guide plate 112, thence through the eyelets in the guide plates 113 and 114 and then the threads which are to be woven into the upper shed are passed through the upper eyelets and the threads which are to be woven into the lower shed are passed through the lower eyelets in the guide plate 115. From this point each of the weft

threads is passed through the eyelet in its respective heddle 118, then passed between the lay 35, hand rail 34, and the ends of the upper wefts are attached to the edge of the upper face of the cloth and the lower wefts 5 are attached to the edge of the lower face of the cloth in any suitable manner, such as by tying.

Assuming that the warp threads (which 10 may be single or double as shown) have been threaded from the main warp beam through the eyelets of their respective heddles in order to form the upper and lower warp sheds, and in case the plush is being woven the pile warp threads 135 and 135' 15 have been passed from the pile warp beam and through the respective heddles for forming the pile shed, and the pattern chain has been placed upon the pattern cylinder. 20 The machine is now ready for operation.

The shipper handle 38 which is formed of spring metal is pulled toward the warp until it rests in the locking groove 153. This action shifts the belt on the pulley 37 so 25 that the gear 39 is set in motion and this gear rotates the gear 41 which in turn rotates the drive shaft 42. The cam drums 76 being secured on the drive shaft are rotated and the followers 88 will move along the cam ridges 77 so as to push the slide bars 84 outward in the brackets 86 and 87. This movement of the slide bars which 30 carry the depending legs 92 will push the links 94 so as to operate the lever 97 to move the cross heads and incidentally the needles 35 55 and carriers 60 respectively toward the centers of the warp sheds.

Previous, however, to the movement of the carrier and needle, the pattern chain has 40 operated two of the heddles which carry the warp threads and has raised a warp thread of selected color to a position directly in line with the path of travel of each of the carriers which, upon actuation, carry the 45 selected wefts to the approximate center of the sheds and deliver the said wefts to the needles which have moved to that point simultaneously with said carriers. The engagement of the carriers and needles and the 50 manner of delivering the thread from the former to the latter are illustrated in Figure 18.

As soon as the needles 55 have been fully 55 retracted from their respective sheds, the lay and hand rail carrying the reed are swung forward on their swords 36 in order to beat the weft threads into the fell of the face and back of the cloth. The weft threads 60 thus pushed forward will strike against the knives 141 and tilt the same to raise the latches 137 and 137' so that the fingers 140 and 140' on the upper end of the bell crank, which is operated by the cam 132 on the 65 drive shaft 42, will pass under the rear wall

of said latches and within the recess 149 in the slide 138.

When the knives are tilted to their fixed limits, the pressure of the weft threads against the same will sever the threads and release them from the needles and the weft threads will be beaten into the fell, the ends thereof, however, extending from the edge of the woven fabric.

During the time that the reed is beating 75 the weft threads into the fell, the cam followers will be passing along the dwells 78 on the cam ridges so that the needles and carriers will momentarily remain stationary. At this time, the pattern chain will also 80 operate the heddles to change the warp shed and the pile shed and operate the heddles to lower the weft threads just used and position other threads in line with the travel of the carriers.

The loom is now again operated by the cam ridges 77 in the manner just described and this is repeated in precisely the same manner throughout the weaving operation.

The eyelets in the guide plates are arranged to provide just sufficient tension to 90 prevent any snarling of the weft threads and at the same time permit them to be readily passed into the respective warp sheds so that there will be no breakage of 95 the weft threads which would stop the loom and tend to produce defective fabric.

Of course, the loom herein shown and described may be modified and changed in various ways without departing from the 100 invention herein set forth and hereafter claimed.

The invention is hereby claimed as follows:—

1. In a loom for weaving double fabric, 105 means to provide concurrent and successive warp sheds, a plurality of weft threads adjacent said sheds, means for selectively raising one of said threads for each shed, means for engaging and carrying said selected weft threads to the approximate center of 110 said sheds, and means for receiving and disengaging said weft threads and carrying the same to the other side of said sheds.

2. In a loom for weaving double fabric, 115 means to provide concurrent and successive warp sheds, a plurality of weft threads adjacent said sheds, means for selectively raising one of said threads for each of said sheds, carriers for engaging and carrying said selected weft threads to the approximate center of said sheds, and needles for receiving and disengaging said weft threads and carrying the same to the other side of 120 said sheds.

3. In a loom for weaving double fabric, means for providing a plurality of warp sheds, a plurality of weft threads each carried by a heddle controlled by a pattern chain, and means for simultaneously passing 125

130

- a selected weft thread through each shed.
4. In a loom for weaving double fabric, means for providing a plurality of warp sheds, a plurality of weft threads each carried by a heddle controlled by a pattern chain, and carriers and needles for simultaneously passing a selected weft thread through each shed.
5. In a loom for weaving double fabric, means for providing a plurality of warp sheds, a plurality of weft threads each carried by a heddle controlled by a pattern chain, and reciprocating means for simultaneously passing a selected weft thread through each shed.
- 10 6. In a loom for weaving double fabric, means for providing a plurality of warp sheds, a plurality of weft threads each carried by a heddle controlled by a pattern chain, and a plurality of reciprocating carriers and reciprocating needles for simultaneously passing selected weft threads through each shed.
- 15 7. In a loom for weaving double fabric, harness means controlled by a pattern chain for forming concurrent and successive warp sheds, a plurality of weft threads normally disposed remote from the side of the shed, reciprocating carriers and reciprocating needles adapted to enter the shed from opposite sides and meet in the approximate center thereof, means for successively positioning selected weft threads for engagement by said carriers and delivery to said needles at the approximate center of the shed whereby said weft threads are drawn completely through said sheds upon the retraction of said needles, means engaging said weft threads when the same are beat into the fell of the cloth to sever said threads and release same from said needles, and means controlled by said last named means to stop said loom when any weft thread is omitted.
- 20 8. In a loom for weaving double fabric, harness means controlled by a pattern chain for forming concurrent and successive warp sheds, a plurality of weft threads normally disposed remote from the side of the shed, reciprocating carriers and reciprocating needles adapted to enter the shed from opposite sides and meet in the approximate center thereof, means for successively positioning selected weft threads for engagement by said carriers and delivery to said needles at the approximate center of the shed whereby said weft threads are drawn completely through said sheds upon the retraction of said needles, means engaging said weft threads when the same are beat into the fell of the cloth to sever said threads and release same from said needles, and means comprising a bell crank operating a slide controlled by said last named means to stop said loom when any weft thread is omitted.
- 25 9. In a loom for weaving double fabric, harness means controlled by a pattern chain for forming concurrent and successive warp sheds, a plurality of weft threads normally disposed remote from the side of the shed, reciprocating carriers and reciprocating needles adapted to enter the shed from opposite sides and meet in the approximate center thereof, means for successively positioning selected weft threads for engagement by said carriers and delivery to said needles at the approximate center of the shed whereby said weft threads are drawn completely through said sheds upon the retraction of said needles, means engaging said weft threads when the same are beat into the fell of the cloth to sever said threads and release same from said needles, and means comprising a bell crank operating a slide controlled by said last named means to stop said loom when any weft thread is omitted.
- 30 10. In a loom for weaving double fabric, harness means controlled by a pattern chain for forming concurrent and successive warp sheds, a plurality of weft threads normally disposed remote from the side of the sheds, reciprocating carriers and reciprocating needles adapted to enter the sheds from opposite sides and meet in the approximate center thereof, heddles individually operated by the pattern chain for successively positioning selected weft threads for engagement by said carriers and delivery to the needles at the approximate center of each shed whereby said weft threads are drawn completely through said sheds upon the retraction of said needles, means engaging said weft threads when same are beat into the fell of the fabric to sever said threads and release same from said needles, and means comprising a bell crank operating a slide controlled by said last named means to stop said loom when any weft thread is omitted.
- 35 11. In a loom for weaving double fabric, harness means controlled by a pattern chain for forming concurrent and successive warp sheds, a plurality of weft threads normally disposed remote from the side of the sheds, reciprocating carriers and reciprocating needles adapted to enter the sheds from opposite sides and meet in the approximate center thereof, heddles individually operated by the pattern chain for successively positioning selected weft threads for engagement by said carriers and delivery to the needles at the approximate center of each shed whereby said weft threads are drawn completely through said sheds upon the retraction of said needles, tiltable knives engaging said weft threads when same are beat into the fell of the cloth to sever said threads to release same from said needles, and means comprising a bell crank operating a slide controlled by said knives to stop said loom when any weft is omitted.
- 40 12. A loom for weaving double fabric comprising means for providing concurrent

warp sheds, means to engage weft threads and to carry the same into said sheds and to present a portion of each weft at right angles to the direction of travel thereof, and means to receive and disengage said weft threads and carry same through said warp sheds.

13. A loom for weaving double fabric comprising means for providing concurrent warp sheds, means to engage weft threads and to carry the same into said sheds and to present a portion of each weft at right angles to the direction of travel thereof, and means to engage the right angular parts of said threads, disengage said threads from said engaging means, and carry same through said warp sheds.

14. A loom for weaving double fabric comprising means for providing concurrent and successive warp sheds, separate means slidably mounted on each side of said loom adapted to approach the approximate center of said sheds, and the means on one side adapted to engage and carry a looped weft thread and to present a portion thereof at right angles to the direction of its travel, and the means on the other side adapted to engage the right angular portion of said thread and disengage it therefrom, and means for retracting said carrying and receiving means from said sheds.

15. A loom for weaving double fabric comprising means for providing concurrent and successive warp sheds, cam operated carriers each adapted to carry a looped weft thread to the approximate center of the sheds and to present a portion at right angles to the direction of travel thereof, cam operated needles adapted to engage the right angular portion and disengage said looped threads from said carriers, and means for retracting said carriers and needles from said sheds.

16. In a loom for weaving double fabric, means to provide concurrent and successive warp sheds, a plurality of weft threads in selective arrangement, cam operated means moving simultaneously from each side of the sheds and adapted to approach the center of each shed, the means on one side being adapted to carry selected weft threads and to present a portion thereof at right angles to the direction of travel, and the means on the other side adapted to engage the right angular portion and to disengage the said weft threads therefrom at the approximate centers of the sheds, and means for simultaneously retracting each of said moving means.

17. In a loom for weaving double fabric, harness means controlled by a pattern chain for forming a plurality of concurrent and successive warp sheds, a plurality of weft threads normally disposed remote from the side of the head, a reciprocating carrier and a reciprocating needle adapted to enter

each shed from opposite sides and meet in the approximate center thereof, heddles operated by the pattern chain for successively positioning selected weft threads for engagement by the carriers, said carriers being forked so as to present a portion of said weft thread at right angles to the direction of travel of said carrier, and to permit the reciprocating needles to enter said fork to engage the right angular portion to disengage the weft threads from said carriers and carry the same completely through said warp sheds.

18. In a loom for weaving double fabric, harness means controlled by a pattern chain for forming a plurality of concurrent and successive warp sheds, a plurality of weft threads normally disposed remote from the side of the head, a reciprocating carrier and a reciprocating needle adapted to enter each shed from opposite sides and meet in the approximate center thereof, heddles operated by the pattern chain for successively positioning selected weft threads for engagement by the carriers, said carriers being forked so as to present a portion of said weft thread at right angles to the direction of travel of said carrier, and to permit the reciprocating needles to enter said fork to engage the right angular portion to disengage the weft threads from said carriers and carry the same completely through said warp sheds, and knife means engaged by said weft threads to sever the same and disengage them from said needle after being drawn completely through the warp sheds.

19. In a loom for weaving double fabric, harness means controlled by a pattern chain for forming a plurality of concurrent and successive warp sheds, a plurality of weft threads normally disposed remote from the side of the head, a reciprocating carrier and a reciprocating needle adapted to enter each shed from opposite sides and meet in the approximate center thereof, heddles operated by the pattern chain for successively positioning selected weft threads for engagement by the carriers, said carriers being forked so as to present a portion of said weft thread at right angles to the direction of travel of said carrier, and to permit the reciprocating needles to enter said fork to engage the right angular portion to disengage the weft threads from said carriers and carry the same completely through said warp sheds, and knife means engaged by said weft threads to sever the same and disengage them from said needle after being drawn completely through the warp sheds, and in the absence of said weft threads or either of them, to operate to stop said loom.

In testimony whereof I have signed my name to this specification.

FRANCIS E. ASHTON. 136
